AIR CONDITIONING DEVICE

Willard M. Johnson, Kansas City, Mo., assignor
to Conditionaire Company, Kansas City, Mo., a
corporation

Application June 18, 1931. Serial No. 545,164

7 Claims. (Cl. 126—116)

This invention relates to an air conditioning device for conditioning air in buildings and the like, and has for its principal object to provide a more economic and efficient air conditioner which may be installed in small out of the way spaces and particularly in buildings constructed without basements.

In accomplishing these and other objects of the invention, I have provided improved details of structure, the preferred form of which is illustrated in the accompanying drawings, wherein:

Fig. 1 is a perspective view of an air conditioning device constructed in accordance with my invention.

Fig. 2 is a detail perspective view of the air heating element as viewed from the burner side.

Fig. 3 is a similar view of the heating element as viewed from the gas outlet side.

Fig. 4 is a horizontal sectional view through the device on the line 4—4, Fig. 5.

Fig. 5 is a vertical central sectional view on the line 5—5, Fig. 4.

Fig. 6 is a cross sectional view on the line 6—6, Fig. 5.

Referring more in detail to the drawings:

1 designates a horizontally positioned housing having top and bottom walls 2 and 3, side walls 4 and 5, and inwardly converging end walls 6 and 7, as best illustrated in Fig. 1. The end walls 6 and 7 have connected thereto an air inlet conduit 8 and an air outlet conduit 9, respectively, whereby air to be conditioned may be passed to and from the housing 1. The conduits 8 and 9 may be connected by suitable branch pipes (not shown) with the respective rooms of a building in which the device is installed.

Positioned in the housing 1 and dividing it into an air intake chamber 10 at one end, adjacent the intake conduit 8, and an outlet chamber 11 at the other, adjacent the discharge conduit 9, is a heating element now described for heating the air discharged through the housing by a circulating fan 12 positioned in the outlet end of the conduit 8.

The heating element is best illustrated in Figs. 2 and 3 and includes a substantially rectangular shaped burner compartment 13 having end walls 14 and 15 extending laterally across the interior of the housing 1 and connected by a bottom wall 16 spaced from the bottom wall of the housing to provide an air passageway 17 for a purpose later described. The end walls of the burner compartment are connected to

and supported by the side wall 4 of the housing in alignment with a door opening 18, through which access may be had to the interior of the compartment.

The side walls 14 and 15 are provided with upwardly extending portions 19 and 20 which are connected by a top wall 21 and a connecting side wall 22 spaced inwardly from the side wall 5 of the housing to provide a passageway 23 for air at the side of the heating element.

Supported in the extensions 19 and 20 of the end walls and extending horizontally therebetween, are a plurality of staggered tubes 24 through which air may be passed directly through the hottest zone of the heating chamber. The heat is confined around the tubes by the walls 19—20 and 21—22 respectively and the lower edge of the wall 22 is bent laterally as at 25 to close the space between the wall 22 and the wall of the housing above the burner chamber, as best illustrated in Fig. 6.

The top wall 21 preferably terminates short of the side walls 14 and 15 to provide a rectangular shaped outlet opening 26 through which the products of combustion are discharged from the heating chamber into an offtake conduit 27 later described.

The side of the burner and heating chambers opposite to the wall 22 is closed by a wall 28 that is spaced from the side wall 4 of the housing 1 to provide room for an air passageway 29 and a downwardly directed portion 30 of the conduit 27.

The outlet conduit 27 for the products of combustion preferably includes a plurality of spaced inter-connected horizontally extending portions 31 and 32 forming loops extending back and forth across the housing at a point above the burner chamber and the upper loop is connected with the portion 30 extending downwardly in the space between the wall of the housing and the rear wall of the heating chamber.

The vertical portion of the conduit extends into substantial alignment with the bottom of the burner chamber and is directed outwardly through the wall of the housing to form a neck 33 which may be connected to a suitable flue, not shown. It is thus apparent that the gases from the burner chamber will travel upwardly around the tubes and out through the opening 26 and through the loops of the gas conduit, giving off their heat to the air which passes through the narrow spaces 34 formed between the loops.

The hot gases therefore travel in tortuous paths and are retained for a considerable time before they are allowed to escape to the flue so that the major portion of the heat which 5 would normally escape to the flue is transferred to the air traveling through the passageways formed by the respective loops of the hot gas conduit.

In order that the heat from the heating chamber and the gas conduit may be confined and retained from the outer walls of the housing, and to provide additional heated surfaces for the air to wipe against, I provide a liner 36 that is spaced from the side and top walls of 10 the housing, as best illustrated in Fig. 6.

The burner chamber may be provided with any suitable type of gas burner 37 which may be connected to a gas supply pipe 38 having a regulating valve 39 for controlling flow of 20 gas and regulating the size of the flame.

In order that the air traveling through the passageway 29 may be divided into thin streams, I provide a baffle plate 40 which is supported between the conduit 30 and the wall 28 by suitable 25 ties 41 as best shown in Fig. 6. The gas passing through the outlet 26 may also be retarded by a baffle 42 extending from the wall 28.

In order that all of the air discharged by the fan may be directed through and above 30 the heating element, I provide a hinged damper 44 for closing the passageway 17 below the heater element. The damper is preferably mounted on a rod 45 which is rotatably mounted in the side walls of the housing and operable 35 exteriorly thereof by a suitable lever 46. The damper normally inclines downwardly toward the fan 12 and has a laterally depending flange 47 that hooks over a partition wall 48 extending across the bottom of the housing between its 40 side walls 4 and 5.

The action of the fan 12 tends to dry the air, and, in order to restore its moisture content, a body of water 49 is carried in the bottom of the housing below the heating element as best 45 illustrated in Figs. 5 and 6. The water is supplied through a pipe 50 extending through the bottom of the pan and its level is controlled by a suitable float controlled valve 51 on the outlet end of the pipe.

50 The water is vaporized by the heat radiating from the bottom portion of the burner chamber and the air leaking past the damper 44 draws the vapors into the hot air chamber to mix with the heated air and restore its proper humidity. The burner 37 may be supplied with secondary air to support combustion through a pipe 52 which conveys the air from the exterior of the building and discharges it into the burner chamber.

60 The portion of air conditioning apparatus thus far described is for heating the air drawn through the conduit 8 and in order that the apparatus may also be used for cooling the air if desired, the air may be diverted through the 65 passageway 17 and over the upper surface of the water 49 by swinging the damper 44 upwardly as shown in dotted lines, Fig. 5. The air is cooled and washed by a spray of water discharged from a horizontal pipe 53 positioned 70 below the pivot rod of the damper and having spray nozzles 54, the water spray being controlled by a valve 55 exteriorly of the housing.

When the damper 44 is swung upwardly to direct the air through the passageway 17, the 75 free end thereof terminates short of the upper

wall of the housing 1, and to cooperate therewith for closing the open space therebetween I provide a second damper 56 which is mounted on a rod 57 extending through the housing and operable by a lever 58, shown in Fig. 1. The free end of the damper 56 is provided with a hook flange 59 for interlocking with the flange 47 on the damper 44, to retain the dampers in functional position. The bottom of the housing is also provided with a suitable overflow pipe 60 to carry off water discharged from the spray 54.

A heating device constructed and assembled as described may be mounted in any convenient location in a building or it may be located in the 80 basement and suspended from the floor joist and connected with the intake conduit 8 and with the exhaust conduit 9 for the hot gases.

The burner may be connected to a suitable gas supply and the water connections connected to 95 the water spray and to the float valve. When the device is used to heat the air, the damper 44 is moved to direct the air through the heating element and the burner lighted. The fan is then operated to blow the air through the tubes 100 and around the loops of the exhaust gas conduit.

The air is divided into thin streams and discharged into the opposite end of the housing for discharge through the conduit 9. The heat radiating from the bottom of the burner housing 105 will vaporize the water carried in the bottom of the housing to restore proper humidity of the heated air discharged into the conduit 9.

When the apparatus is to be used for cooling the air the dampers 44 and 56 will be adjusted 110 to divert the air across the body of water and through the spray from the pipe 53. The spray of water washes the air and cools it as it passes therethrough for discharge into the conduit 9 for distribution through the rooms.

When the device is used for heating the air it is obvious that the air discharged through the housing is divided into a plurality of streams due to the narrow passageways through the heating element and that the air streams contact and 120 wipe over a maximum area of heated surfaces so that substantially all of the heat units generated by the burner are absorbed by the air streams before the products of combustion can pass from the outlet 33 to the flue.

125 It is also obvious that the heating device is compact and may be installed in available spaces without taking up an undue amount of space, as is the case of present warm air heating apparatus.

130 What I claim and desire to secure by Letters Patent is:

1. An air conditioning device comprising a horizontally positioned housing having side walls, an air inlet conduit at one end of the 135 housing, an air outlet conduit at the other end of the housing, a heating element positioned in the housing and spaced from the walls of the housing to form air passageways therebetween, means for directing air through the housing in 140 wiping contact with the heating element and the walls of the housing, means for retaining a body of water covering the bottom of the housing for adding moisture to the air, and means located between the air inlet and the heating 145 element for selectively diverting the air below the heating element and over the body of water in the housing when the heating element is not in use.

2. An air conditioning device comprising a hori- 150

zontally positioned housing having side walls, an air inlet conduit at one end of the housing, an air outlet conduit at the other end of the housing, a heating element positioned in the housing and spaced from the walls of the housing to form air passageways therebetween, means for retaining a body of water covering the bottom of the housing for adding moisture to the air, and means between the inlet and the heating element for selectively directing air through the housing in wiping contact with the heating element and the walls of the housing when the heating element is effective and over the body of water when the heating element is not effective.

18 3. An air conditioning device comprising a horizontally positioned housing having side walls, an air inlet conduit at one end of the housing, an air outlet conduit at the other end of the housing, a heating element positioned in the housing and spaced from the walls of the housing to form air passageways therebetween, a damper in the housing between the inlet and the heating element for directing air through the housing in wiping contact with the heating element and the walls of the housing, means for retaining a body of water covering the bottom of the housing for adding moisture to the air, a water spray discharging into the housing below said damper, and means cooperating with said damper for diverting the air below the heating element and through said water spray when the heating element is not in use.

4. An air conditioning device comprising a housing, a heating chamber in the housing, a plurality of tubes extending through the heating chamber, a burner in the heating chamber, a conduit extending in loops from the heating chamber and terminating in a downwardly extending portion adjacent the heating chamber to conduct products of combustion from the heating chamber, a deflector plate between the downwardly extending portion of the conduit and the heating chamber, and means for discharging air through said tubes and across the loops of the conduit for heating the air.

45 5. In an air conditioning device, a heating ele-

ment comprising a heating chamber, air tubes extending through the heating chamber, a burner in the heating chamber for heating the air passing through said tubes, an outlet at the top of the heating chamber, a conduit communicating with the outlet and having horizontally spaced legs spaced from the top of the heating chamber to form horizontal air passageways therebetween extending parallel with the air tubes, and a vertically arranged conduit communicating with said first named conduit and spaced from a side wall of the heating chamber to provide an air passageway therebetween.

6. An air conditioning device comprising a horizontally positioned housing having an air inlet conduit at one end and an air outlet conduit at the other, a heating element positioned in the housing intermediate the conduits having a plurality of horizontally extending passageways, means for discharging air through said passageways to heat the air, water spraying means in the housing, and means located between said air discharging means and the heating element for diverting air through water sprayed from said spraying means and below the heating element to protect the heating element from moisture carried by the air when the heating element is not effective.

7. An air conditioning device comprising a horizontally positioned housing having an air inlet conduit at one end and an air outlet conduit at the other, a heating chamber positioned in the housing intermediate the conduits having a plurality of passageways extending therethrough, means in the housing for discharging air through said passageways to heat the air, water spraying means in the housing, and a damper in the housing between the inlet and the heating element for diverting the air through water discharged from the spraying means and below the heating chamber.
